230,503

FOLDABLE LADDER

George Harvey Emmons, 11 S. 12th St.,
Marshalltown, Iowa 50158

Filed Dec. 29, 1971, Ser. No. 213,778

Term of patent 14 years

Int. Cl. D6—06

U.S. Cl. D54—1 A

FIG. 5

FIG. 2

FIG. 1

FIG. 4FIG. 3FIG. 1 is a perspective front view of a foldable ladder in open position showing my new design,

FIG. 2 is a rear elevational view of the ladder in FIG. 1,

FIG. 3 is a side elevational view thereof.

FIG. 4 is a side elevational view opposite to that shown in FIG. 3, and

FIG. 5 is a fragmentary perspective view of the upper extremity of this ladder showing a second embodiment thereof, the lower extremity being the same as in FIG. 1.

I claim:

The ornamental design for a foldable ladder, as shown and described.
